UNITED STATES PATENT OFFICE.

CECIL E. PAYNE, OF BATH, MAINE.

SHIP'S STEERING-GEAR.

1,309,076.

Specification of Letters Patent.

Patented July 8, 1919.

Application filed February 25, 1919. Serial No. 279,107.

To all whom it may concern:

Be it known that I, CECIL E. PAYNE, a citizen of the United States, and resident of Bath, Maine, have invented certain new and useful Improvements in Ships' Steering-Gears, of which the following is a specification.

My present invention relates to improvements in ships' steering gear of the type in which fluid pressure is used to effect the movements of the rudder, which pressure is secured through a pump driven by a motor running constantly in one direction, such for example as an electric motor.

The object of the invention is to devise a simple, economical, durable and efficient form of apparatus and particularly to provide a system by which the proper movements may be imparted to the rudder without the use of a reversible pump for securing the proper flow of pressure fluid to operate the steering ram in both directions.

With these and other objects in view the invention includes the novel features of construction and arrangement of parts hereinafter described and particularly defined by the appended claims.

An embodiment of my invention is illustrated in the accompanying drawing in which Figure 1 is a diagrammatic view but with parts shown in section, and Fig. 2 is an enlarged sectional view of the valve and associated parts shown partly in plan.

Referring by reference characters to this drawing the numeral 1 designates the rudder post or head carrying the tiller arm 2, which is connected by a slot and pivoted block arrangement with a member 3, which

forms continuations of or connects a pair of rams or pistons working respectively in the opposed cylinders 4 and 4^a, which parts may be of the ordinary or any desired construction. The motive fluid is supplied to

these cylinders to operate the rams by pipes 5 and 6, which are connected by a by-pass controlled by a valve 7 so as to allow the fluid to pass readily from one pipe to the other, when hand steering is desired as more specifically referred to hereinafter.

8 designates a non-reversible motor, such as an electric motor, the shaft of which is connected to the shaft of a non-reversible, but variable stroke pump of any approved type capable of supplying fluid at any de-

sired pressure from zero up to the maximum required. 17 designates the discharge pipe of the pump which is connected to the chamber 19 of the reversing valve 10, while 18 designates the return pipe to the pump from 60 the valve chambers 20 and 20^a.

Pipes 5 and 6 connect respectively to chambers 21, which are designed to be placed either in communication with the chambers 19 and 20 by the reversing valve 65 10. Oppositely acting spring pressed safety valves 22 are provided, controlling passages 22^a directly connecting the chambers 21, so that if pressure on either side runs too high direct communication between the ram 70 cylinders is afforded.

The pump is adapted to be automatically adjusted to force fluid through the discharge pipe by a spring 14 acting on rod 13, which in turn rocks gear segment 15, which 75 latter operates the gear 16 on the trunnion arm of the pump.

When the valve is in neutral position pressure is held or built up in chamber 19 and branch 19^a, which latter communicates 80 with a cylinder 12 containing a piston 12^a fast on or connected with rod 13. The pressure of fluid against piston 12^a moves rod 13 to set and hold the pump at zero, as long as the reversing valve is in neutral position. 85

The shifting of the valve in either direction places valve chamber 19 in communication with one or the other of chambers 21 and connected pipe 5 or 6 with the corresponding ram cylinder and at the same time 90 places the other ram cylinder in communication with the return pipe 18 through pipe 5 or 6 and chamber 20.

As soon as the reversing valve has thus been operated the escape of fluid from chamber 95 19 reduces the pressure on the piston 12^a allowing the spring to open up the pump which thereafter continues to force fluid into the passage 21 just opened.

24 designates a controlling element which 100 is to be operated by any suitable means, such as the ordinary telemotor apparatus, and which is connected to a lever 23, pivotally connected at 23^a to the stem 11 of the reversing valve, the other end of the lever 105 being connected to the ram member 7^a. This lever 23 is therefore a floating lever and as soon as motion of rod 24 is stopped the movement of the ram member 3, acting on the opposite end of the lever automatically 110

restores the reversing valve to neutral position, building up pressure in chamber 19 and through piston 12^a and its connections reducing the stroke of the pump.

- 5 Any suitable means may be provided for hand steering when valve 7 has been operated to place both passages 21 in communication.

What I claim is:

- 10 1. In a steering gear, a steering motor, a continuously operable variable stroke irreversible pump for supplying motive fluid to actuate said motor, a reversing valve for reversing the flow of fluid between the pump and motor adapted in one position to cut off said flow, and means whereby the building up of said flow varies the stroke of the pump.
- 20 2. In a steering gear, a steering motor, a continuously operable variable stroke irreversible pump for supplying motive fluid to actuate said motor, a reversing valve for reversing the flow of fluid between said pump and motor adapted in neutral position to interrupt said flow, a spring tending normally to increase the stroke of the pump and a piston operated by the building up of pressure when said valve is in neutral position to reduce the stroke of the pump.
- 30 3. In a steering gear, a steering motor, a continuously operable, variable stroke irreversible pump having pipe connections for supplying motive fluid to actuate said motor, valve means for reversing said connections and for stopping the flow of fluid, and pressure controlled means for varying

the stroke of the pump when the valve means is operated.

4. In a steering gear, a motor, a continuously operable variable stroke irreversible pump having fluid conduits for supplying motive fluid to actuate said motor, safety valve means for allowing said fluid to pass directly from either of said conduits to the other under excess pressure, valve means for reversing the flow of fluid and for stopping the flow, and pressure controlled means for varying the stroke of the pump.

5. In a steering gear, a motor, a controlling element, a continuously operable variable stroke irreversible pump, conduits for conducting the fluid between said pump and motor, a valve for reversing the flow of fluid in said conduits, said valve when in neutral position stopping said flow, pressure controlled means for varying the stroke of the pump, and a floating element having operative connection with said controlling element and said valve and said motor.

6. In a steering gear, a steering motor, a continuously operable variable stroke irreversible pump operatively connected with said motor valve means for reversing the flow of fluid and for stopping said flow, means for operating said valve, and means for automatically increasing the stroke of the pump when the valve means is operated to permit the flow of liquid and retarding it when the flow of fluid is stopped by the valve.

In testimony whereof, I affix my signature.
CECIL E. PAINE.
